PRINTING SCALE

Arthur Hahn, Balingen, Germany; vested in the
Alien Property CustodianApplication March 6, 1939, Serial No. 260,243
In Germany March 9, 1938

4 Claims. (Cl. 265—5)

The invention relates to a printing device for adjusting weight inclination weighing machines, in which the values of the weights to be placed on by the weigher after the normal weighing range is exceeded are recorded with the weight values of the normal range of the machine, which are determined by exploration of a disc bearing devices to be explored, rotatable about an axis with the tilting weight device.

The known devices of this kind have the disadvantage that if too large or too small an adjusting weight is placed on, i. e. if the feeler or explorer for the disc is within the dead angle between the limits of zero and the maximum load, either the figure 0 or the figure corresponding to the maximum value of the disc is printed. There are no means for ensuring that the adjusting weights are placed on or taken off in the correct amount, and are taken into account in the printing.

The object of the invention is to remove this disadvantage. This is effected according to the invention, in a weighing machine of the kind above referred to, by the provision of a locking device for the driving means of the printing mechanism, which device comes into operation if the disc is brought outside the exploring position or range as a result of too large or too small an adjusting weight being added. The locking device is preferably under the control of the disc.

On the disc there is preferably provided, in the angle between the devices for zero and maximum value, a raised or projecting part which when the disc is out of exploring position as the result of too large or too small an adjusting weight being added, lies in the path of a feeler moved by the driving means of the printing device, complete movement of which feeler is necessary for releasing the normally locked driving means for the printing device.

According to a further feature of the invention the feeler moved by the driving means of the printing mechanism serves to control a locking pawl, which engages with play in the said driving means, and is lifted out of the driving means if the feeler executes a full operative movement, but remains in engagement with the driving means if the raised or projecting part on the disc prevents the complete movement of the feeler.

The movement of the feeler co-operating with the raised part of the disc is effected by the driving means of the printing mechanism preferably through the medium of a spring, and the locking pawl engaging in the driving means of the print-

ing mechanism is under the control of a spring normally holding it in engagement with the driving means, and of a linkage controlled by the feeler, the spring tending at the same time to draw the feeler into its rest position.

An embodiment of the invention is illustrated by way of example in the accompanying drawings, in which Figure 1 shows the measuring head of an inclination adjusting weight weighing machine in elevation, with part of the scale removed.

Figure 2 is a plan view of the printing device of the weighing machine.

Figure 3 is a section through the printing device on the line III—III of Figure 2.

Figure 4 is a section through the printing device on the line IV—IV of Figure 3.

On the axle 1 of the inclination system of the weighing machine, which system is known in itself, and is consequently not illustrated in detail, are rigidly mounted an indicator 3 movable over a scale 2, and the disc 4 bearing devices to be explored. This disc is provided with devices to be explored in a manner likewise known per se. In the embodiment illustrated by way of example

25 the disc has devices for hundreds, tens, and units. The devices for the hundreds consists of steps 5 formed at the periphery of the disc. The devices for the tens are formed by the step-wise offset outer edge 6 of a number of recesses 7 corresponding to the hundreds devices, and the units devices are formed by the step-wise offset inner edge 8 of these recesses.

The exploration of the devices 5, 6, 8 is effected in the axial direction of the disc 4 by three step-wise offset feelers 9, 10 and 11 (Figure 2). The feeler 9 serves for exploring the hundreds devices, the feeler 10 for exploring the tens devices, and the feeler 11 for exploring the units devices. Each feeler carries at its rear end an eye 12 to

40 which is secured the one end of a spring 13, the other end of which engages a transverse rod 14 of the fixed frame 15 of the printing device, the springs tending to draw the feelers towards the disc 4.

45 Each feeler carries on its under side a projection 16. The projections 16 abut against a transverse rod 17 of a slide 18 movable in the direction of the feeler movement. The slide is constructed, on its under-side, as a rack 19, which is in engagement with a gear-wheel 20. See Figures 3 and 4. The gear-wheel 20 is mounted on the axle 21, which carries a second gear-wheel 22, which is in engagement with a gear-wheel 25 on the shaft 23 of the hand crank

50 24. If the hand crank is rotated in the direc-
55 60 65 70 75 80 85 90 95

tion of the arrow (Figure 3) then the gear-wheel 20 moves the slide 18 and therewith the transverse rod 17 in the direction of the disc 4, so that the feelers 9, 10, 11 are released and likewise move towards the disc under the influence of the springs 13 and can register with the devices 5, 6, 8 located before them at the time.

The feelers 10 and 11 transmit their exploring movement directly to the type wheels 26, 27. See Figures 2 and 3. For this purpose the feelers 10 and 11 are constructed at their rear ends as racks 28, 29, which are in engagement with gear-wheels 30, 31 on the shafts of the type wheels 26, 27. The printing type wheels are displaced in accordance with the magnitude of the exploring movement of the feelers 10, 11 which move in the direction of the disc 4 until one of their steps strikes a step of the disc.

The exploring movement of the feeler 9 for the hundreds is transmitted to the printing type wheel 32, which moreover is pre-adjustable to definite values in accordance with the adjusting weights added. The rack 33 serving for adjustment of the printing type wheel 32, which rack is in engagement with the gear wheel 34 on the shaft of the printing type wheel 32, is not rigidly connected with the feeler 9, but lies adjacent to this feeler and laterally thereof, extends out beyond the disc 4 and is bent downwardly and to one side as at 35. A spring 136 tends to draw the rack 34 into the position corresponding to the zero position of the printing type wheel 32. To the frame 15 of the printing device is hinged a bell crank lever 36 to which the adjusting weights are coupled by means of the rod 37. According to the value of the adjusting weight, the bell crank lever 36 presses the rack 33 towards the right in Figures 2 and 3 through the intermediary of roller 38, and thereby effects a preadjustment of the printing type wheel 32 in accordance with the adjusting weight which has been added.

The feeler 9 has a lateral projection 39, and on the upper side of the rack 33 there are provided in the vicinity of this projection a number of projections 40, 41, 42 which upon movement of the feeler 9 towards the disc 4 extend into the path of the projection 39.

It should be understood that when the weighing machine is operating without additional weights the projection 39 lies between the projections 41 and 42. When only one additional weight is used the projection lies between the projections 41 and 42, and when two additional weights are used the position of the projections 40, 41 and 42 relative to the projection 39 is that which is illustrated in Figure 2. The particular means for effecting relative movement between the elements 39, 40, 41 and 42 so as to place them in the relative positions stated according to the number of weights used is not illustrated in detail or claimed herein, this mechanism per se being covered in detail in my copending application for U. S. Letters Patent, Serial Number 308,277.

When the feelers 9, 10 and 11 are released in the manner hereinbefore described by the hand crank 24, said feelers move toward the disk 4, the feeler 9 being moved by the lateral projection 39 and taking with it the rack 33. Movement of the rack 33 serves to properly place the printing type wheel 32.

After adjustment of the printing type wheels 26, 27, 32 has been effected, the printing is

effected by pressing a piece of paper or the like lying on the printing plate 43 against the printing type wheels. The printing plate 43 is arranged on the one end of a double-armed pressure stirrup 45 rotatably mounted at 44, which stirrup is controlled by a cam 46. This cam is mounted on a shaft 47 which carries a gear wheel 48 which is in engagement with the gear wheel 25 on the shaft 23 of the hand crank. Upon rotation of the hand crank 24 in the direction of the arrow the cam 46 presses on the end of the pressure stirrup 45, which is provided with a roller 49, and presses the printing plate 43 against the printing type wheels.

The object of the invention is to prevent printing if the dead angle α of the disc 4, which corresponds to the dead angle γ of the scale 2, is located opposite the feelers 9, 10, 11. In order to achieve this the printing device is held locked when the disc is in this position. The locking is effected by a locking pawl 50 which is mounted on the hand crank shaft 23 and is freely rotatable thereon, the pawl being normally held in engagement with a double cam 52 on the shaft 47, by a spring 51. The double cam is provided with two recesses 53 and 54. The free end of the locking pawl 50 lies in the recess 53 extending over a certain part of the periphery of the cam. In the recess 54 lies a spring 55 which extends through an opening of the frame of the printing device, and is secured to an angle feeler 57 pivoted at 56. The feeler is connected at its upper end by a rod 58 with one end of the spring 51, the other end of which is anchored to the frame of the printing device. The rear end of the locking pawl 50 is pivoted to the rod 58 at 59.

If the hand crank 24 is rotated in the direction of the arrow, the free end of the locking pawl 50 slides along in the recess 53 of the double cam 52. At the same time the double cam presses the spring 55 out of the recess 54 and therewith swings the angle feeler 57 in the direction of the disc 4. By this displacement of the feeler 57 the locking pawl 50 is moved out of the recess 53 of the double cam 52 by the rod 58, so that upon further rotation of the hand crank the cam 46 engages the roller 49 of the stirrup 45 and printing is effected.

In order to prevent printing if the dead angle α of the disc is located opposite the feelers 9, 10, 11 a raised part 60 is provided on the disc 4 over this angle, which part lies in front of the angle feeler 57 with the disc in the said position. If, with the disc in this position, the hand crank 24 is rotated, the free end of the angle feeler 57 abuts against the raised part 60. The raised part therefore prevents the full deflection of the angle feeler, the result of which is that the locking pawl 50 is not lifted out of the recess 53 of the double cam 52 by the rod 58, but remains in engagement with the recess and prevents a further rotation of the hand crank 24.

The raised part 60, the extent of which corresponds to the dead angle of the disc, thus prevents the accomplishment of a printing operation so long as the dead angle of the disc lies opposite the feelers 9, 10 and 11 as the result of excessive or insufficient load. In order to permit of printing, the weigher is obliged to add or remove an adjusting weight according to the circumstances; since it is only by the removal or addition of an adjusting weight that the dead angle of the disc is moved into a position in which the raised part 60 does not lie in front of the feelers 9, 10, 11. The printing of false

weighing results by means of the printing mechanism is thereby prevented.

I claim:

1. In a printing scale of the type wherein the value of the weight which is added after the normal weighing range is exceeded, is printed together with the other weight values which are determined by the feeler exploration of a rotatable member formed with weight value indicia corresponding to the normal weight values up to a dead angle between the zero point and the maximum load point; the provision of a printing mechanism for printing the weight of the mass being weighed, driving means for the printing mechanism, a feeler device associated with said driving means, and means providing a control area associated with the rotatable member of the weighing system and extending over the dead angle range and with which the feeler device cooperates for locking the driving means of the printing mechanism, and said feeler device being operable to release the driving means of the printing mechanism when the area on the movable part of the weighing system is out of the range of the said feeler device.

2. In a printing scale of the type wherein the value of the weight which is added after the normal weighing range is exceeded is printed, together with the other weight values which are determined by the feeler exploration of a rotatable disc formed with weight value indicia cor-

- responding to the normal weight values up to a dead angle between the zero point and the maximum load point; the provision of a printing mechanism for printing the weight of the mass being weighed, driving means for the printing mechanism, a feeler device associated with said driving means, and means providing a raised portion on the surface of said disc over the dead angle range and against which the feeler device 5 is adapted to abut for locking the driving means of the printing mechanism, and said feeler device being operable to release the driving means of the printing mechanism when the said raised portion is out of the range of said feeler device.
- 10 3. In a printing scale, as claimed in claim 1, wherein a control lever for the driving means of the printing mechanism simultaneously serves as the control lever for the feeler device which effects locking of the printing mechanism.
- 15 4. In a printing scale, as claimed in claim 1, wherein a locking pawl engages the driving means of the printing mechanism to lock the same and wherein spring means are provided 20 for normally forcing said pawl into engagement with the driving means but releasable therefrom by operation of the feeler device when the control area on the movable part of the weighing system is out of range of the feeler device.
